RESETTING MECHANISM FOR GASOLINE
DISPENSING PUMPS

Robert H. Hill and Burdette W. Foss, Fort Wayne,
Ind., assignors to Tokheim Oil Tank and Pump
Company, Fort Wayne, Ind., a corporation of
Indiana

Application February 28, 1947, Serial No. 731,636

28 Claims. (Cl. 222—33)

1

This invention relates to reset mechanisms for resetting the computer head of a so-called computing device and more particularly to a gasoline pump of the computer type.

Among the objects of the present invention is to provide an hydraulic mechanism operated by the pressure in the dispensing line for automatically actuating the reset mechanism prior to the initiation of the dispensing operation and operable from the pressure of the pump which causes the dispensing flow and whereby the hydraulic pressure may be utilized to control the speed of the resetting mechanism whereby to avoid injury to such mechanism.

Yet another object of the invention is to provide an hydraulic mechanism for resetting the computer mechanism wherein means is provided whereby to prevent a false registration of the computer mechanism.

Yet another object of the invention resides in providing hydraulic reset mechanism for the computer head including means which will permit the pump motor switch lever being thrown to a position to stop the pump but which will prevent the switch from being thrown again to a second "on" position until the reset mechanism has been restored to an original initial position from which resetting starts, thereby precluding false registration of the numeral wheels.

Yet another object of the invention resides in providing mechanism associated with the switch for the pump motor constructed and arranged so that if the pump motor switch is once thrown to the pump "off" position, the reset mechanism must complete its cycle of operations before such pump motor switch can again be turned to a pump "on" position.

Yet another object of the invention resides in providing, in an hydraulic reset mechanism for a computer head, means for preventing partial actuation of the shutter mechanism or of the reset mechanism due to momentary failure of the power line or due to the momentary passage of relatively large volumes of air through the air separator such as would cause such a material reduction of pressure in the dispensing line to affect the hydraulic reset mechanism.

Yet another object of the invention resides in providing means controlled by the "on" position of the motor pump switch lever for precluding movement of the hydraulic reset mechanism away from dispensing position due to the momentary passage of air through the air separator or the momentary failure of the electrical system.

Yet another object of the present invention resides in providing an hydraulic reset mechanism

2

for a gasoline computer pump possessing all of the advantages of the foregoing.

Another object of the invention is to provide a resetting device which will reset the computer at a fixed constant speed.

Another object of the invention resides in providing a resetting device which will prevent the operation of the resetting mechanism during any discharge of liquid from the dispensing nozzle.

These and other objects of the invention will be apparent from a perusal of the following specification when taken in connection with the accompanying drawings, wherein:

Figure 1 is a view of a gasoline computer pump provided with the instant invention;

Figure 2 is a schematic view of the flow lines of the pump and incorporating parts of the present invention;

Figure 3 is a diagrammatic representation of the hydraulic reset mechanism which includes the air separator or air release mechanism of the Bechtold Patent 1,868,444, issued July 19, 1932, the details of the valve mechanism being more specifically shown in Figure 6 of the drawings;

Figure 4 represents the same diagrammatic view showing the motor pump switch lever thrown to the "on" position, the resetting operation having taken place and dispensing in operation;

Figure 5 is a corresponding view of the parts showing the hydraulic reset mechanism returning to normal position and the motor pump switch lever in "off" position;

Figure 6 is a detail view of the valve construction showing the air release mechanism of the aforesaid Bechtold patent, and also shown in the Foss Patent 2,289,003, issued July 7, 1942;

Figure 7 is a view of the torque responsive clutch showing the position of parts before the pump is started;

Figure 8 is a view of the same showing the position of the parts after the pump is started and the reset shaft turned one and one eighth of a revolution;

Figure 9 is a view showing the position of the parts an instant after the completion of one and one eighth revolution;

Figure 10 is a view showing the position of the parts an instant after the cam is released;

Figure 11 is a sectional view of the torque responsive clutch taken on the line 11—11 of Figure 7;

Figure 12 is an exploded view showing the various parts of the torque responsive clutch;

Figure 13 is a view, similar to Figure 4, but

3

incorporating additional safety structures for insuring proper operation of the parts;

Figure 14 shows a view of a modified or commercial form of the hydraulic reset mechanism;

Figure 15 is an enlarged view of the hydraulic cylinder and its piston and rack and the reset latching mechanism;

Figure 16 is a section on the line 16-16 of Figure 14 showing the details of construction of the improved clutch; and

Figure 17 is a section on line 17-17 of Figure 16.

In the present commercial type of gasoline computer pump the computer mechanism, which is of the well known Veeder-Root type, requires a manual one and one eighth forward turn to complete the resetting operation. This forward turn is followed by a one eighth turn in the reverse direction for the purpose of raising the shutters which mask the numeral wheels during the resetting operation. The one eighth reverse turn for clearing the shutters from the numeral wheels is actuated by spring means in the computer itself and this reverse turn occurs at the termination of the forward one and one eighth turn and is occasioned by the computing mechanism coming against a positive stop, which is then followed by the aforesaid reverse turn. One or all of the following patents owned by Veeder-Root, Incorporated, of Hartford, Connecticut, discloses the particular type of mechanism herein set forth: Slye 2,264,557, of December 2, 1941; Wild 2,274,115, of February 24, 1942; Slye 2,282,-678, of May 12, 1942. In addition, it is to be noted that this type of Veeder-Root computing mechanism has been in commercial use and sale in practically all of the computer type pumps now in use in the United States. They are made by Veeder-Root, Incorporated, of Hartford, Connecticut, and are known as computer pumps, and the computing mechanism is constructed and operates in accordance with the disclosure of this application. Furthermore they are described in repair part manuals of Veeder-Root, Incorporated and also of many of the gasoline pump manufacturers, including The Wayne Pump Company, S. F. Bowser & Company, Incorporated, The Tokheim Oil Tank and Pump Company, of Fort Wayne, Indiana, the Erie Company, of Erie, Pennsylvania, and many others too numerous to mention. In short, the construction and operation of this type of computer is well known to those skilled in the art.

Referring now to the drawings in detail, in Figure 1 there is shown a more or less conventional type of dispensing pump preferably of the computer type which is adapted not only to compute the volume but also the price. The invention is equally adaptable to any type of volume and/or price indicating pump wherein indicating or registering mechanism is synchronically operated in accordance with the liquid flow through the metering or liquid measuring mechanism. In the present instance, the computing mechanism is shown as positively driven by the meter shaft, but other adaptations are within the contemplation of this invention.

Referring now to Figure 1, the invention shows the usual type of angle iron frame or skeleton upright 1 which supports the conventional type of housing 2 and within which housing is positioned the other internal units of the pump such as the electric motor 3 driving the pump 4 through suitable gearing such as the belt 5. The pump 4 is adapted to draw gasoline from a supply tank,

4

upwardly through the pipe 6 forming a part of the dispensing line, into the suction chamber 7 and an air separator or air release mechanism shown particularly in Figure 3. In the present instance, the air separator is of the type preferably as shown in a patent to Bechtold, No. 1,868,-444, patented July 19, 1932, comprising a housing or other casing having internal partitions. The pump has an inlet chamber or suction chamber 7 connected with the pipe 6 and connecting with a preferably cylindrical screen 8 through which the entering gasoline flows on its way to the pump 4. The pump is shown preferably as in internal gear type but any type of pump may be utilized. The gasoline is discharged from the port 10 into a separation chamber 11 which is adapted to separate air and/or vapor from the gasoline, discharging the air and/or vapor to atmosphere while passing the gasoline to and through the dispensing line. In the air separator any air entering the chamber 11 will necessarily rise to the top and pass through the small orifice 12 into the superior float chamber 13. If no air be present, a small amount of gasoline will pass through this orifice 12 when the pump is running, but if or when the amount of gasoline in the chamber 13 rises to such a level as to raise the float 14, this in turn, opens the valve 15. This additional flow of liquid is thus returned to the suction side of the pump 4 by means of the conduit 16. The float chamber 13 is preferably covered by a metal dome 17 to which in the present invention are connected two tubes 18 and 19. Tube 19 serves as a constantly open vent to the atmosphere. This tube passes upwardly and out through the housing 2, as shown in Figure 1. Thus the float chamber 13 is always under normal atmospheric pressure.

Tube 18, which is not disclosed in the prior Bechtold patent, leads to the upper end of a cylinder 20 hereinafter more fully described in detail.

As in accordance with the prior Bechtold patent, and as shown in detail in Figure 6 of the present drawings, the separation chamber 11 is provided with two pressure operated valves 21 and 22 normally held closed by springs 23 and 24 respectively. Valve 22 is known as the by-pass valve, while valve 21 is a regulating valve. In the dividing partition 25 which divides the pressure chamber from the float chamber, there are provided two openings adapted to receive cylinders 26. The upper ends of these cylinders have an annular flange 27 which fits into a counterbore in the casting. On top of these flanges are covers 28 which are clamped thereon by the bar 29 and screws 30. In the center of these cylinder covers 28 is a dome-like portion 31 apertured centrally as at 32. The bar clamp 29 is provided with holes 33 which register with the vent holes 32 whereby to allow the upper ends of these cylinders 26 to be open to atmospheric pressure through the gasoline in the float chamber 13 and the atmospheric vent tube 19. Within each cylinder 26 is a piston 34 secured to valve rods 35 and 36. On the lower ends of the cylinders 26 are spring retainer disks 37 having a large clearance hole in their centers to allow liquid under pressure to act upon the bottoms of the pistons 34 when the pump and motor are operating. Compression springs 23 and 24 are disposed between the respective valves and the retainers 37 for holding the valves closed until sufficient pressure is created in the separation chamber 11 by the pump 4 whereby to act upon the pistons 34.

and open the valves against their springs. Below the valve 22 is a by-pass duct 38 which opens into the suction chamber 7. Below the valve 21 is a duct 39 the top of which is attached to a pipe 40 constituting a part of the dispensing line and leading in the inlet side of the meter 41. Attached to the side of the separator chamber 11 is another tube 42 the other end of which is attached to the bottom of the cylinder 20 of the resetting device.

From the outlet side of the meter, the dispensing line 43 flows through a liquid flow gauge 45 and from thence the gasoline passes through the usual type of flexible hose 46 mounted on the outside of the housing or casing 2. This hose 46 is provided with the conventional type of nozzle valve 47. The meter 41 drives the computer 49 by means of the drive shaft coupling 50. The computer may be of the conventional type used today or may be just a simple type of counter. For this discussion, the mechanism is devised for resetting the type of computer generally known as a Veeder-Root, manufactured by Veeder-Root, Incorporated of Hartford, Connecticut. On this type of computer the reset shaft 51 does not rotate when the computer is being driven. To reset, the shaft must be turned 405 degrees counter-clockwise, looking at the computer from the hose side, as viewed in Figure 3, and it will then rock back 45 degrees.

By reference to Figures 1, 2 and 3, the cylinder 20 shown in Figure 3 is suitably mounted on the support frame 1 of the pump. This cylinder 20 is provided at its upper end with a relatively long bearing 52 in which rotates a pinion shaft 54. The opposite wall of the cylinder 20 is provided with an elongated sleeve-like portion 56 for purposes hereinafter recited, and the top of the cylinder 20 is provided with a longitudinal housing or guideway 58 to accommodate the uppermost position of a rack about to be described.

The pinion shaft 54 is provided on its inner end with a pinion 60 adapted to mesh with an elongated rack 62 normally disposed within the cylinder and carrying at its lower end a piston 66. A coil spring 68 normally confined between the upper end of the cylinder 20 and the top side of the piston 66 normally serves to force the piston down to the position shown in Figure 3. The interior of the cylinder 20 is provided with a guideway 70 to the rack. The top 72 of the rack, as shown more clearly in Figure 5, is provided with a bevelled surface 74 for cooperation with a preferably round nose 76 of a plunger 78 which has a collar 80 confining a spring 82 between it and the shoulder 84 of the bearing sleeve-like portion 56 whereby the plunger 78 is normally pressed toward the rack to maintain the rounded nose portion 76 in contact with the rack. The hollowed outer end 86 of the plunger 78 is provided with a second plunger the stem 88 of which is normally projected outwardly by means of a second coil spring 90. A threaded thimble 92 closes the end of the plunger 78 about the shank 88. The inner end of the shank is provided with a head which is adapted to compress the spring 90 in the bored portion of the plunger 78. The outer end of the shank 88 is provided with a preferably squared end forming a latch to cooperate with a shoulder portion 94 on the inner rounded end 96 of the switch lever 98 which is pivoted at 100. The upper end of this switch lever may be formed preferably in any well known manner to receive thereon the hose nozzle 47 which is of customary construction. The usual

means is provided in association with the housing for preventing the movement of the switch to the pump "on" position while the hose nozzle is resting on the switch lever or on the stationary support associated with the switch lever, as is well known in the art. The hose nozzle 47, it will be understood, is provided with the customary valve 47a and the valve actuating member 47b.

Associated with the liquid dispensing line 43 coming from the meter 41 is a fitting 95 which connects as at 97 with that port of the dispensing line 43 into which the meter 41 discharges. This fitting has a lower portion providing a bearing 101 with a valve seat 102 and an outlet pipe 104 which connects with that portion of the dispensing line 43 that is beyond the usual type of sight glass 45. In addition the fitting is provided with a delivery valve 106 adapted to be urged onto the valve seat 102 by a coil spring 108. The valve 106 has a stem 110 which slides in an aperture in the bearing 101. The bearing is shown as being at the upper portion of the elongated guideway 58 in which the rack 62 reciprocates. It will thus be seen that the valve 106 is in the dispensing line and is normally closed on the valve seat 102.

A torque responsive clutch mechanism 112 is located between the pinion shaft 54 and the computer reset shaft 51, as shown clearly in Figure 3, and its function is to provide a driving agency between the hydraulically actuated pinion shaft 54 and the reset shaft 51 of the computer. The present type of computer which rotates 405 degrees forwardly to reset the numeral wheels of the computer and then 45 degrees rearwardly to remove the shutters from the reset numerals, requires a type of clutch which will permit this. In addition, the clutch must be constructed and arranged to permit the rack 62 of the hydraulically actuated mechanism which gears with the pinion 60 to move downwardly its full length stroke after the upward full length stroke of the rack which is the actual reset portion of the movement of the rack. The downward stroke of the movement of the rack is a cocking or conditioning movement of the piston so as to put the reset mechanism in condition for a subsequent operation. The torque responsive clutch, as shown in Figures 11 and 12 of the drawings, comprises an outer shell 112 of generally cup-like construction, which shell has an axial integral hub 114 which is pinned as at 118 to the pinion shaft 54. The shell 112 is provided with a slot 120 in its annular rim and is likewise provided with an outstanding, radially extending lug 124. A torsion spring 126 through which the driving takes place has one end 128 which is anchored in the slot 120 of the shell and has an opposite inner end 130 which is anchored as hereinafter described. The spring houses within the hollow shell 112. As shown in Figure 12, the lug 124 has a portion 125 that extends outwardly beyond the edge or mouth of the shell 112. A disk 132 is provided with a hub 134. The hub in turn is provided with a groove or slot 136. The hub is adapted to surround the pinion shaft 54 and has a bearing thereon and rotates with respect thereto. The hub extends into the shell 112 and is housed thereby. The inner end 130 of the spring 126 is anchored in the slot 136 of the hub 134. The disk is provided with an offset portion 138 to receive a pivot pin 140 which pivots a trigger 142 to the disk. This trigger has an outwardly extending leg 144 which leg is bent at right angles to provide a portion out of

the plane of the trigger 142. In addition, the opposite leg 148 of the trigger 142 projects normally outwardly beyond the periphery of the disk 132 being normally held in this position by means of a coil spring 150 which is anchored to the outer end of the leg 144 and likewise to the disk 132. The disk 132 is also provided with a radially outstanding, substantially square ear 152 which cooperates with the lug 125 on the shell 112. The trigger portion 148 also cooperates with the lug 124 on the shell 112 during a certain part of the driving operation. A second disk 154 is provided with an annular collar 156 extending from one face thereof. It is provided with an oppositely extending sleeve 161 extending centrally thereof. This sleeve 161 is provided with diametrically disposed slots 162 for receiving driving pins 166 formed on the inner end 164 of a short shaft. This short shaft in turn is provided with a ball-like head 167 and oppositely extending pins 169 which engage in slots 171 on the end of the computer shaft 51. In addition, the sleeve 161 is provided with a groove 168 to receive a spring 172 which engages in a grooved end 174 of the driving shaft 54. The computer reset shaft 51, as is well known, is adapted to be operated in one direction, preferably forwardly, to turn the numeral wheels to zero for the reset operation. This forward or clockwise turning of the reset shaft is to the extent of 405 degrees forwardly to reset the numeral wheels and computer, and then the shaft, under spring action of a spring in the computer itself, turns the reset shaft rearwardly 45 degrees to remove the shutters from the reset numerals, as is well known in the art. The clutch herein disclosed accomplishes this function. The second disk 154 is provided with a cam surface 168 and an abrupt shoulder 170 thereon. This cam surface 168 and the shoulder 170 are adapted to cooperate with the upturned end 144 of the trigger mechanism 142 carried by the first disk 132. The pinion drive shaft 54 extends through this sleeve. The groove 174 of the shaft 54 will lie opposite the slot 168 so that the spring inserted in this slot will lie in the groove 174 of the shaft 54.

Pivoted as at 176 to the inner end 96 of the switch lever 98 is a switch rod 178, the inner end carrying a switch 180 which is adapted to make electrical contacts with the electrical circuit of the motor 3 which drives the pump 4, in a well known manner.

By reference to Figure 3, the liquid drain pipe 18 connects to the top portion of the hydraulic cylinder 20. The opposite end of this pipe 18 connects with the float chamber 13.

In the operation of the entire mechanism, assuming that due to a previous operation of the computing dispensing pump the numeral wheels have stopped at 5 gallons and the corresponding total cost wheels of the computer have stopped at \$1.00, which would be the total cost of 5 gallons at 20c per gallon, when it is desired to make a second and subsequent dispensing the operator takes the nozzle 47 from the hook and manually raises the switch lever 98. Prior to raising the switch lever the condition of the mechanism is shown in Figure 3. In this position the rack 62 will be completely downward because both the top and bottom of the piston are at atmospheric pressure when the pump is idle, thereby allowing the spring 68 to push the piston downward to the bottommost position, as shown in Figure 3. At this time the nozzle valve is closed and the valve 106 is closed, and the two valves 21 and 22

are closed, as stated. The operator then removes the nozzle from its hook and raises the switch lever 98 to the "on" position of the pump, as shown in Figure 4. This immediately, through the rod 178, closes the switch and starts the pump motor to start the pump 4. Pressure in the chamber 11 is immediately created. The spring of valve 21 is set for approximately 10 pounds. The spring of the by-pass valve 22 is set for 20 pounds. The spring 68 on the hydraulic piston cylinder chamber 20 is set for less than 20 pounds. The spring 108 is set for more than 22 pounds. As soon as the pump is started, the rack 62 is raised and in so raising the rack will turn the pinion 60 on the shaft 54. Figure 7 of the drawings shows the position of the parts of the clutch before the pump is started. Figure 8 shows the position of the parts after the pump has been started, and shows the reset shaft 51 turning forwardly or clockwise one and one eighth revolutions. During the turning of the reset shaft the first one eighth of a turn, the spring in the computer is energized. The turning of the reset shaft by the turning of the drive shaft 54 is accomplished in the following way. As a result of the pressure created in the chamber 11 liquid will be forced through the pipe 42 into the hydraulic cylinder 20 to raise the piston 66 against the tension of the spring 68. (This will force the rack upwardly and push the plunger 78 outwardly so that its outer end contacts the rounded periphery of the cam 96 as shown in Figure 4.) As the rack 62 moves upwardly the pinion 60 is rotated to rotate the shaft 54. As soon as the pump is started during the raising of the rack, the shell 112, being connected to the shaft 54, will be rotated in a clockwise direction. This shell 112 is connected as at 128 with the outer end of the spring 126, and the inner end 130 of the spring is connected to the collar 134 of the disk 132 by means of the slot 136, see Figure 12. This spring then acts as a driver for rotating the disk 132 in a forward, clockwise direction. The disk 132 thus rotating forwardly will carry the trigger mechanism 142 in a forward, clockwise manner around with it, and since the toe 144 of this trigger is engaging the shoulder 170 of the disk 154, this latter disk 154 will likewise be turned in a forward, clockwise direction. It will be remembered that the spring 150 maintains this toe in contact with the shoulder 170. This second disk 154, being connected by means of the slot 162 and the pins 166, pins 169 and slot 171 of the shaft 51, will turn likewise to drive the reset shaft 51 forwardly in a clockwise direction. After one and one eighth revolutions of the reset shaft, the reset mechanism comes against a stop and can go no further forwardly. But since the shell 112 is still driving the disk 132, and since the disk mechanism 132 carrying the trigger mechanism 142 is engaging the now stationary shoulder 170 on the now stationary disk 154, the disk being thus arrested, the lug 124 on the shell 112 which is still revolving forwardly clockwise will strike the end 148 of the trigger mechanism to push the same about its pivot 140 in a clockwise direction to shift the toe 144 of the trigger mechanism away from the shoulder 170 of the disk 154, thereby to break the driving connection between the driven disk 132 and the driven disk 154. This position is indicated in Figure 9 where the toe 144 is just leaving the shoulder 170. As soon as this release occurs, the disk 154 will rotate backwardly in a counterclockwise direction 45 degrees to move the shutters from the reset numerals. This

backward movement is caused by the spring in the computer mechanism itself, which spring is present in practically all standard types of computers, such for instance as the computers now manufactured by Veeder-Root, Incorporated, and in use on practically all types of computer pumps, such for instance as those manufactured by The Wayne Pump Company, Tokheim Oil Tank and Pump Company, and Gilbert & Barker Manufacturing Company. The return of this disk 154 is shown in Figure 10. Simultaneously with the return of this disk 154 the toe 152 on the disk 132, still moving forwardly clockwise, contacts the lug 124 of the shell, due to the action of the spring 126.

Referring to the foregoing cycle of operations, it is to be noticed that during the preliminary rotation of the reset shaft 51 the first action is to move the shutters over the numeral wheels and thereafter to shift the numeral wheels toward zero setting. As the rack continues to rise, the resetting will continue to the position where the upper end of the rack reaches the line A in Figure 4 of the drawings. This latter position of the rack corresponds to the completion of the resetting operation by the computer mechanism of the computer itself and corresponds to a situation where a portion of the operative mechanism of the computer contacts the movable stop. That is, when the computer shaft comes to the end of its rotating reset motion, it engages a stop within the computer proper. This creates excessive torque on the computer reset shaft which in turn moves lug 124 away from the ear 152 (Figure 9), thereby engaging the upper arm 148 of the trigger and disengaging the trigger from the cam 154 to break the drive between the disk 132 and the disk 154. During the rotation of the reset shaft, that is, during at least one eighth of the reset revolution of the computer, a torque spring in the computer is energized so that at the conclusion of the reset operation when the reset mechanism strikes the stop and the driving connection between the disks 154 and 132 is broken, this energized spring then comes into action so that when in position corresponding to the top of the rack reaching the line A, the spring reverses the reset operation one eighth of a turn, whereby to remove the shutters from the now reset counter wheels. This action takes place after the disengaged position is reached, just as the parts move beyond the position shown in Figure 9, so that the tang 144 is free of the shoulder 170 and thereafter rides upon the smooth portion 168 of the cam disk 154. By this time, the rack has continued on up to the position shown at B in Figure 4 where the tip of the rack strikes the shank of the valve 106 and opens it against the pressure of the spring 108. This position is shown in Figure 4. This valve 106, which constitutes a delivery valve or a valve controlling the flow of dispensing fluid in the delivery line, is thus held in open position as long as the resetting piston 66 is held in its topmost position, as shown in Figure 4. At this time no dispensing occurs because the nozzle valve is not open. As the pressure in the chamber 11 continues to build up, and when twenty pounds pressure has been reached the by-pass valve 22 will open to permit the liquid to by-pass around the pump, as is well known in the art. Prior to this, to-wit, at ten pounds pressure, the valve 21 has been opened by the pressure occurring against the underside of the piston of the valve as set forth in the prior patent to Bechtold, but no flow takes place through the flow

line 40-43 due to the fact that the nozzle valve 47a is still unopened. As soon as the nozzle valve 47a is opened, dispensing flow will immediately take place under the influence of the rotating pump 4, and the valve 106 will thus be held open by rack 62 to permit this. Immediately upon the completion of that particular dispensing operation the operator will then return the switch lever 98 to the down or "off" position to stop the pump, 10 see Figure 5. Immediately the pressure in the chamber 11 drops, and this drop correspondingly reduces the pressure in the hydraulic cylinder 20. When the pressure gets low enough, the spring 68 will start forcing the piston 66 down. This 15 will carry the rack down so that when the top of the rack descends to point A (see Figure 4) the valve 106 will close under the action of the spring 108. As shown in Figure 5, the rack continues to descend to recock or recondition the reset mechanism for the next dispensing and its subsequently following reset operation. As long as the rack is in an upward position the blunt nose of the plunger 78 will bear or slide against the side of the rack to, maintain the latch 88 against the 20 rounded side 96 of the switch 98. However, when the switch arm is lowered, this shoulder 94 will be brought above the position of the latch so that the latch will then snap under it as shown in Figure 5, and thereafter it will be impossible to 25 raise the switch 98 until the rack 62 has moved back to its lowermost position, as shown in Figure 3, which corresponds to the completion of the recock or reconditioning position of the reset mechanism. The reverse movement of the rack, 30 which brings about a reverse rotation of the shaft 54, and hence a reverse rotation of the shell 112, is permitted since the pivoted trip 148 carried by the shell will revolve in an opposite direction, the tang 144 thereof moving in such a direction as to 35 pass the shouldered portion 170 of the disk 168 on the pinion shaft.

From the foregoing it will be apparent that one of the great advantages of the present construction of hydraulic automatic reset mechanism is that the speed of the reset mechanism can be controlled to whatever appears to be the most satisfactory speed, because the hydraulic reset mechanism provides a controlled and fixed pressure for actuating the piston which supplies the power for the reset mechanism. The rate of speed of reset can be controlled by controlling the size of the pipe 42. The speed of the cocking action is controlled by the strength of spring 68 and the size of the orifice 12 and size of pipe 42.

Furthermore, the present reset mechanism provides means for protecting the operator of the pump, or the owner of the pump, against dispensing any gasoline prior to the completion of the reset due to the fact that the valve 106 cannot be opened until after the computer head has been completely reset, and further in view of the fact that it is controlled by the reset mechanism itself. In fact, in the present device the power has been disconnected from the computer before this valve can open. The latter part of the stroke of the rack which has been disconnected from the computer goes upward some distance after the line A is reached, before it fully opens the valve 106 at the line B. By reference to the drawings, the line A shows the point at which the reset rack 62 is disconnected from the computer through the clutch 112. As the nose 72 of the rack 62 passes beyond the point A it contacts the lower end of the valve stem 110 and begins to open the valve 106. From the point A to the

point B the valve 106 is opening and at the point B the valve 106 is sufficiently open. Hence until the rack reaches the point A, at which time the resetting has been completed and the rack disconnected, the valve 106 will not be opened to permit flow through the line 104 and thus there is provided means for preventing the liquid from flowing through the dispensing line until the completion of the reset operation and until the reset shaft is disconnected by means of the clutch 112 from the computer.

In addition, means is also provided in the form of the shoulder 94 on the motor switch 98 and its cooperative latch 88 for preventing the switch from being turned to "off" position and then turned on again immediately in an attempt to stop the computer in the middle of the reset operation. This means, herein shown in the form of the latch 88, prevents the motor or pump switch being turned to "on" position again after once being turned to "off" position, until the reset mechanism has been returned to its normal position. Figure 5 shows the position where the rack is descending and shows that the motor pump switch 98 is locked in "off" position until the rack 62 completely descends to the position shown in Figure 3, which means that the operator cannot stop the resetting mechanism in the middle of a cocking cycle because if he did he could cause the computer to show a false reading. The switch locking mechanism therefore precludes the operator from stopping the reset operation when half-way through, so that a dispensing operation for a subsequent purchaser would not start with the dials away from zero position, and hence the subsequent purchaser would not be defrauded and charged for more gasoline than he actually received. This mechanism prevents the operator from restarting the motor when the resetting rack is in a partially downward position due to the fact that the rack itself must go all the way down in order to permit the latch to be pushed inwardly by a spring to escape the shoulder of the switch lever. This mechanism will ensure that the reset mechanism when once put into operation by the opening of the switch, and followed by the raising of the switch followed by the lowering of the switch to stop dispensing, must move through a full cycle before the switch can be thrown on again.

In the event that a type of computer is used wherein the reset shaft turns through two complete revolutions but has no partial backward travel, a simple type of overrunning clutch or a friction clutch may be used in place of the clutch 112.

In certain instances it is desirable to provide means interconnecting the switch lever and the rack for holding the rack in full raised position up to the point B where the valve 106 is maintained in open position during dispensing so as to preclude the partial lowering of the rack, as when a large amount of air passes through the air release chamber, or due to a momentary failure of the current in the line as distinguished from an opening of the switch lever 98. Such means is illustrated in Figure 13. This mechanism comprises a wedge-shaped abutment 184 formed on the side of the rack 62 and having an upper wedge-shaped face and providing a lower shoulder. In cooperation with this wedge-shaped abutment there is provided a second latch 186 passing through the desired portion of the wall 58, which second latch has a head 188 normally pressed by a spring 180 and confined with

in a hollow plunger 192 on the end of a rod 184. This rod is pivoted at 196 to a bell crank lever 198 pivoted at 200 and pivotally connected as at 202 by means of an arm 204 to the switch arm 98 by means of the pivotal connection 206, so that when the switch arm is raised the arm 194 will be pushed inwardly, tending to push against the side of the rack. When the rack is raised, and after arm 98 has been raised to "pump on" position, the upper surface of abutment 184 will ride past the latch 186, after which the latter will spring under the shoulder of the abutment whereby to maintain the rack in raised position until such time as the switch lever is thrown to the "off" position, which immediately withdraws the second latch 186 so that thereafter the rack 62 is free to descend. By thus holding the rack in raised position continuously during dispensing and until the switch lever 98 is restored to "pump off" position, a relatively large momentary volume of air passing through the chamber 11 even though it causes a drop in the chamber and a drop in the pressure in the cylinder 20 will not permit the valve 106 to be closed under the force of the spring 108. Hence the dispensing line will be kept open. Without this means, if the rack should drop a distance due to the decrease of pressure in the cylinder 20 due in turn to a momentary large volume of air passing through the chamber 11, the dispensing valve would close, and then when the air had passed and the pressure picked up again, the rack would move upwardly again away from its fallen position, and this last raising movement of the rack would throw the shutters of the dials and partially turn the computer dials and the shutters would remain over the dials because the reset operation would not be completed. With the last described mechanism, however, this is impossible because the latching mechanism 186 will hold the rack in its elevated position and will hold the valve 106 open so that the rack cannot drop, and therefore will not drop and then raise again, and will therefore not throw the shutters over the numeral wheels or cause a false movement of the numeral wheels. The fact that the valve 106 is held open during the momentary movement of a large volume of air through the air separator, is immaterial because the valve 21 of the air separator will close at this point and prevent any such air from getting into the dispensing line.

Referring now to the modification shown in Figure 15, only a portion of the structure shown in the prior figures is modified. The modification relates to the construction of the hydraulic cylinder and its rack and the construction of the latching apparatus. In addition, a more simplified construction of clutch is shown. Referring to Figure 15, there is shown a preferably cast cylinder base 208 in which is seated the cylinder 210. The upper end of this cylinder is closed by means of an elongated cylindrical cap 212 which at its upper end 214 is formed of smaller dimensions and terminates in a relatively long barrel-like portion 216, extending considerably beyond the restricted portion 214 and connecting with a fitting 218 in which the valve 106 and its stem 110 are mounted. The hydraulic piston 220 is attached to the bottom of the rack 222 in any suitable manner, as my means of the centralized screw 224 which confines the usual type of circular gasket 226 between the piston and the retaining plate 228. A coil spring 230 is confined 75 between the inner face of the piston 220 and the

upper end of the narrowed portion 214 of the cap 212, the narrowed portion being provided with a shoulder to retain the upper end of the spring.

Mounted in the cap 214 is the pinion shaft 232 on which is mounted the pinion 234. This pinion shaft 232 corresponds with the pinion shaft 54 of Figure 3, and the pinion 234 corresponds with the pinion 60 of Figure 3. This pinion 234 meshes with the teeth 236 of the rack 222. In addition, the upper end of the rack is provided with a narrowed end 237 and an inclined shoulder 240, much like the upper end portion 72 of the rack 62 is formed in Figure 3. The top of the rack operates and reciprocates in the relatively small sleeve-like portion 216 and its upper portion is arranged to contact the lower end of the valve stem 110 in the same way that the rack 62 contacts the valve stem 110 in Figure 3. So also the fitting or cap 214 is provided with an enlarged, inwardly projecting wall portion 242 which is recessed as at 244 to receive a bushing 246. The bushing 246 forms a bearing for a head 248. The head 248 has a threaded internal bore to which is also threaded a sleeve 250 which has an outer bearing in a flanged ring 252 that is bolted as at 254 and 256 to the outer wall of the head 214. The member 250 has a central opening through which reciprocates a latch pin 258 which has a rounded end 260. The other end of the latch pin 258 has a head 262 between which and the inner end of a bore 264 of the first head 240 is located a coil spring 266 which spring tends to force the head 262 of the latch pin 258 normally outwardly. In addition to the movement of the latch pin 258, the latch head 248 also has a movement in and out, toward and away from the line of reciprocation of the rack 222. To accomplish this, the head 248 is provided with an annular shoulder 268 which forms a seat against which a second coil spring 270 is confined. The opposite end of the coil spring is confined against the inner wall of the flange 252. Thus the spring 270 tends to normally force the head 248 inwardly against the rack bar while permitting the head to be moved outwardly by the inclined wall 240 of the rack bar. A spring finger 272 is mounted as at 274 on the cap 214 and has its inner ends pressing against the adjacent wall of the rack 222 whereby normally to keep the teeth of the rack resiliently in contact with the teeth of the pinion 234.

Cooperating with the outer rounded end 260 of the rounded latch 258 is a second latch member 276. This latch is of sector-like conformation and is rigidly mounted on the shaft 278 which is adapted to turn. This shaft 278 corresponds to the shaft 100 on which the switch lever 98 is rigidly mounted so that when the lever is turned the shaft is likewise turned. Hence, when the hose nozzle is placed on the switch 98, as shown more particularly in Figure 5 of the drawings, the lever 98 will be moved to a motor "off" or disconnected position, whereas when the switch lever 98 is raised, the motor will be placed in operative or motor "on" position. The switch latch 276 is provided with a depressed portion 280 which corresponds with the lower point of the cam 96 which is shown directly below the shoulder 94 in Figure 5 of the drawings. The other portion 282 of the latch is provided with a flat or higher surface so that as the latch sector 276 moves angularly with the shaft 278 either the low portion 280 or the higher portion 282 of the latch confronts the rounded end 260 of the latch pin 258. The action of this mechanism is other-

wise exactly like the action of the latch construction shown in Figures 1 to 5.

The modified clutch arrangement is shown particularly in Figures 14, 16 and 17. In Figure 17 the shaft 54 is shown at 284 as being rigidly connected to a collar 286 which in turn is rigidly welded or fixed to a shell-like housing 288. This housing has a punched-in ear 290 to which one end of a coil spring 292 is connected. In addition, the inner end 294 of the shaft 54 is loosely mounted in a hub 296 which is provided with an integral cam 298 and an outwardly extending driving shaft 300 provided with a slotted end 302 for engaging a universal connection with the computer reset shaft 51, as is shown in the prior Figures 11 and 12. The housing 288 is provided with a rivet pin 304 which pivotally supports a latching dog 306 disposed within the housing. This latching dog carries at its outer end an anti-friction roller 308 and is provided at its outer end with a tongue or ear 310 to which is attached the opposite end 312 of the coil spring 292 heretofore referred to. In addition, the cam 298 is provided with a cam surface 314 which terminates in a shoulder 316 which is adjacent a low point 318 of the cam surface, the low point of the cam surface gradually increasing in the manner shown, up to the high point adjacent the shoulder 316. In the operation of this device, when the rack operated shaft 54 or 232 of Figure 15 is turned, upon actuation of the rack in an upward direction, as seen in Figure 15, the pinion will be turned counterclockwise as viewed in Figure 15, which in turn moves the housing 288 counterclockwise and through the pin 304 and the spring 292 causes the roller 308 to engage the shoulder 316 of the cam, and the cam 298 will be turned counterclockwise in the same direction. This counterclockwise movement through this clutch mechanism will thus turn the shaft 300 counterclockwise to cause the reset shaft 51 to move in the same direction to cause the resetting of the computer. When the computer mechanism has reached its positive stop, as hereinbefore explained, in connection with Figures 1 to 5 inclusive and Figures 7 to 12 inclusive, the resistance set up will cause the roller 308 to disengage and move outwardly from the shoulder 316 thereby breaking or unclutching the driving connection which will permit the reset shaft to continue to turn while the computer has stopped. This breaking of the clutch connection permits the rack 222 to continue to move upwardly after the resetting has been completed so as to contact the lower end of the valve stem 110 to open the valve 106.

Obviously the invention is not limited to the specific details of construction disclosed herein but is capable of other modifications and changes without departing from the spirit and scope of the appended claims.

Having thus described the invention, what is claimed as new and desired to be secured by Letters Patent is:

1. A liquid dispensing apparatus comprising a dispensing line adapted to be connected to a source of liquid supply, means for controlling the flow of liquid through the dispensing line, register mechanism operable in accordance with the flow of liquid through the dispensing line, resetting means for the register mechanism, control means for effecting the operation of the register resetting means and the liquid flow control means, said control means including mechanism for operating the flow control means in predetermined

15

timed relation to the operation of the register resetting means and including mechanism operable upon the actuation of the control means for effecting the operation of the liquid flow control means to cause the pressure of the liquid in the dispensing line to cause the complete automatic cyclic operation of the resetting means before the control means can be reoperated to cause a subsequent operation of the liquid flow control means.

2. A liquid dispensing apparatus comprising a dispensing line adapted to be connected to a source of liquid supply, pumping means for forcing liquid through the dispensing line, means including a delivery valve for controlling the flow of liquid through the dispensing line, register mechanism operable in accordance with the flow of liquid through the dispensing line, resetting means for the registering mechanism, and control means for effecting the operation of the pumping means, the operation of the register resetting means, and the operation of the delivery valve, said control means including mechanism operable by pressure of liquid in the dispensing line for effecting the opening of the delivery valve at a predetermined time interval after the operation of the resetting means and for ensuring the completion of the operation of the resetting means prior to a subsequent operation of the pump operating means by said control means.

3. A liquid dispensing apparatus comprising a dispensing line adapted to be connected to a source of liquid supply, pumping means for forcing liquid through said dispensing line including a manually operable switch, means including a delivery valve in the dispensing line for controlling the flow of liquid through the dispensing line, said manually operable switch controlling said pumping means, register mechanism operable in accordance with the flow of liquid through the dispensing line, resetting means for the register mechanism, and common control means for effecting the operation of the register resetting means, and said delivery valve including mechanism operable by pressure of liquid in the dispensing line for effecting the opening of the delivery valve a predetermined time interval after the operation of the register resetting means and for preventing a subsequent operation of the manually controlled switch until the completion of the operation of the resetting means.

4. A liquid dispensing apparatus comprising a dispensing line adapted to be connected to a source of liquid supply, pumping means for pumping liquid through said dispensing line, a motor for driving the pump and a switch operating mechanism for operating the motor, register mechanism operable in accordance with the flow of liquid through the dispensing line, resetting means for the registering mechanism, and control means interconnecting the switch operating mechanism and the resetting mechanism and actuated by pressure of liquid in the dispensing line for preventing the operation of the switch operating mechanism to restart the motor until the resetting mechanism has completed its cycle of operation.

5. A liquid dispensing apparatus comprising a dispensing line adapted to be connected to a source of liquid supply, means including a delivery valve for controlling the flow of liquid through the dispensing line, register mechanism operable in accordance with the flow of liquid through the dispensing line, resetting means for the register mechanism, a pump for forcing liquid

16

through said dispensing line, a motor for the pump, a manually operated switch lever for the motor, an actuatable member adapted to move a predetermined distance upon the operation of the pump by said motor, means operated by the movement of said member for actuating the resetting mechanism and for subsequently opening the delivery valve, and means cooperating with the travel of said member and associated with the switch lever for preventing two consecutive operations of said switch lever unless the resetting mechanism has been completely operated by a predetermined movement of said member.

6. A liquid dispensing apparatus comprising a liquid dispensing line adapted to be connected to a source of liquid supply, a pump in said line, a motor for driving the pump, a manually operated switch member for actuating said motor, means including a delivery valve for controlling the flow of liquid through the dispensing line, register mechanism operable in accordance with the flow of liquid through the dispensing line, a cylinder, a piston in the cylinder, connections from said cylinder to the liquid flow line to cause the operation of said piston upon the creation of a pressure in the flow line, a rack operated by the piston, means actuated by movement of the rack for operating the resetting mechanism, said rack upon a predetermined movement actuating said delivery valve, and a latching device disposed in the path of movement of said rack cooperating with the switch operating mechanism of the motor for preventing two consecutive movements of the switch operating mechanism to pump operating position unless the resetting mechanism has completed its resetting travel.

7. A liquid dispensing apparatus comprising a dispensing line adapted to be connected to a source of liquid supply, means including a delivery valve for controlling the flow of liquid through the dispensing line, register mechanism operable in accordance with the flow of liquid through the dispensing line, resetting means for the register mechanism, a pump for forcing liquid through said dispensing line, a motor for the pump, manually operated switch mechanism for the motor, and control means operable upon the movement of said pump means for effecting the operation of the register resetting means and the delivery valve, said control means including mechanism for effecting the opening of the delivery valve a predetermined time after the operation of the register resetting means and including mechanism for locking the manually operated switch means for subsequent operation until after the completion of the resetting of the rack.

8. A liquid dispensing apparatus comprising a dispensing line adapted to be connected to a source of liquid supply, a pump for forcing liquid through the line, a motor for the pump and a manually operated switch member for controlling the pump motor, means including a delivery valve in the dispensing line for controlling the flow of liquid through said line, register mechanism operable in accordance with the flow of liquid through said line, resetting means for the register mechanism and means actuated by the movement of said switch member for operating the register resetting means and said delivery valve, said means including mechanism for effecting the opening of the delivery valve a predetermined time after the operation of the resetting means and including mechanism for maintaining the delivery valve in

open position until said pump switch operating member is thrown to such a position that the pump motor is rendered inoperative.

9. A liquid dispensing apparatus comprising a dispensing line adapted to be connected to a source of liquid supply, a pump for forcing liquid through the line, a motor for the pump and a manually operated switch member for controlling the pump motor, means including a delivery valve in the dispensing line for controlling the flow of liquid through said line, register mechanism operable in accordance with the flow of liquid through said line, resetting means for the register mechanism and means actuated by the movement of said switch member for operating the register resetting means and said delivery valve, said means including mechanism for effecting the opening of the delivery valve a predetermined time after the operation of the resetting means and including mechanism for preventing momentary closure of the delivery valve under momentary failure in the current in the line as distinguishing from the throwing of the pump motor switch to pump "off" position.

10. A liquid dispensing apparatus comprising a dispensing line adapted to be connected to a source of liquid supply, means including a delivery valve for controlling the flow of liquid through said dispensing line, register mechanism operable in accordance with the flow of liquid through the dispensing line, reset mechanism for the register mechanism, air release mechanism for said dispensing line including a pressure chamber subject to a relatively low pressure when the pump is in operation, an hydraulic cylinder and liquid conduit connecting said pressure chamber with said hydraulic cylinder, a piston in said cylinder, and means actuated by movement of said piston for operating said reset mechanism and for opening said delivery valve, said mechanism effecting the opening of the delivery valve a predetermined time after the operation of the register resetting means, and means for holding said delivery valve in open position during momentary movement of large volumes of air through the air separator.

11. A liquid dispensing apparatus comprising a dispensing line adapted to be connected to a source of liquid supply, means including a delivery valve for controlling the flow of liquid through said dispensing line, register mechanism operable in accordance with the flow of liquid through the dispensing line, reset mechanism for the register mechanism, air release mechanism for said dispensing line including a pressure chamber subject to a relatively low pressure when the pump is in operation, an hydraulic cylinder and liquid conduit connecting said pressure chamber with said hydraulic cylinder, a piston in said cylinder, and means actuated by movement of said piston for operating said reset mechanism and for opening said delivery valve, said mechanism effecting the opening of the delivery valve a predetermined time after the operation of the register resetting means, and means for holding said delivery valve in open position during momentary movement of large volumes of air through the air separator, a pump for forcing liquid through the dispensing line, a motor for driving the pump, a switch operating member for the motor and means interconnecting the switch operating mechanism and said movable member operated and moved by said piston for holding said delivery valve in open position while

said switch operating member is in pump "on" position and during the momentary movement of large volumes of air through the air separator.

12. A liquid dispensing apparatus comprising a dispensing line adapted to be connected to a source of liquid supply, means including a delivery valve for controlling the flow of liquid through said dispensing line, register mechanism operable in accordance with the flow of liquid through the dispensing line, reset mechanism for the register mechanism, air release mechanism for said dispensing line including a pressure chamber subject to a relatively low pressure when the pump is in operation, an hydraulic cylinder and liquid conduit connecting said pressure chamber with said hydraulic cylinder, a piston in said cylinder, and means actuated by movement of said piston for operating said reset mechanism and for opening said delivery valve, said mechanism effecting the opening of the delivery valve a predetermined time after the operation of the register resetting means, means for holding said delivery valve in open position during momentary movement of large volumes of air through the air separator, a pump for forcing liquid through the dispensing line, a motor for driving the pump, a switch operating member for the motor and means interconnecting the switch operating mechanism and said movable member operated and moved by said piston for holding said delivery valve in open position while said switch operating member is in pump "on" position and during the momentary movement of large volumes of air through the air separator, and means for locking said pump switch operating member from subsequent pump operating movement until the completion of the reset operation.

13. In a liquid dispensing apparatus comprising a dispensing line adapted to be connected to a source of liquid supply, means including a delivery valve in said line for controlling the flow of liquid therethrough, registering means operable in accordance with the flow of liquid through said dispensing line, said registering mechanism including shutter mechanism operable to cover the computing indicia, said computing mechanism being of the type requiring a manual one and one eighth forward turn to complete the resetting operation thereof and followed by a one eighth turn in the reverse direction for the purpose of raising the shutters masking the numeral wheels at the termination of the forward one and one eighth turn, said computing mechanism including stop mechanism precluding further forward turning of said computing mechanism after the reset has been accomplished, said resetting means for the register including a reset shaft, a driving shaft for operating said reset shaft, means for actuating said driving shaft in a direction to cause the reset shaft to move one and one eighth turns to effect the resetting thereof and to cause the resetting mechanism to contact the stop and thus to prevent further continued movement of said resetting mechanism, and clutch mechanism inserted between the driving shaft and the reset shaft including a driving element connected to said second shaft, a spring connected to the driving element, a driven element having the spring connected thereto whereby said driven element is rotated by means of said spring upon the rotation of said driving element, said driven element including a pivoted trigger, a second driven element connected with the reset shaft for rotation therewith, said second driven element having a cam thereon, said cam having a shoulder, said

trigger element having a toe adapted drivingly to engage said shoulder whereby upon movement of said driving and first driven element in one direction said toe engaging said shoulder will drive said second driven element in the same direction, and means brought into operation when said reset mechanism contacts the stop in the computer mechanism for breaking the connection between the driving element and said second driven element whereby the spring of the computer turns said second driven element reversely one eighth of a revolution, and means on said first driven element and on said driving element for reconditioning said driving and driven elements for a subsequent operation.

14. In a liquid dispensing apparatus comprising a dispensing line adapted to be connected to a source of liquid supply, means including a delivery valve in said line for controlling the flow of liquid therethrough, registering means operable in accordance with the flow of liquid through said dispensing line, said registering mechanism including shutter mechanism operable to cover the computing indicia, said computing mechanism being of the type requiring a manual one and one eighth forward turn to complete the resetting operation thereof and followed by a one eighth turn in the reverse direction for the purpose of raising the shutters and masking the numeral wheels at the termination of the forward one and one eighth turn, and including a stop mechanism precluding further forward turning of said computing mechanism after the reset has been accomplished, said resetting means for the register including a reset shaft, a driving shaft for operating said reset shaft, means for actuating said driving shaft in a direction to cause the reset shaft to move one and one eighth turns to effect the resetting thereof and to cause the resetting mechanism to stop to prevent further continued movement of said resetting mechanism, and a clutch mechanism inserted between the driving shaft and the reset shaft including a driving element connected to said driving shaft, a spring having one end connected to the same, a driven element having the other end of the spring connected thereto whereby said driven element is rotated by means of said spring upon the rotation of said driving shaft, said driven element having thereon a pivoted trigger, said clutch mechanism including a second driven element connected with the reset shaft for rotation therewith, said second driven element having a cam thereon, said cam having a shoulder, said trigger element having a portion adapted drivingly to engage said shoulder whereby upon movement of said driving and first driven element in one direction said toe engaging said shoulder will drive said driven element in the same direction, and means operable when said reset mechanism is stopped for breaking the connection between the driving element and said second driven element whereby to permit the spring of the computer to turn said second driven element reversely one eighth of a revolution, means on said first driven element and on said driving element for reconditioning said driving and driven elements for a subsequent operation, said means including a radially disposed lug on said first driven element and a spaced lug on said driving element.

15. A clutch for interconnecting a driving shaft and a reset shaft of a computer of the type having a reset shaft inoperable when the computer is being driven and wherein said shaft is turned 405 degrees in one direction to reset the com-

puter and is thereafter stopped, and wherein said reset shaft then rotates reversely 45 degrees, said clutch comprising a driving shaft, a shell driven thereby, a spring connected to the shell, a driving disk associated with said shell, the other end of the spring being connected with said driving disk whereby said driving disk is rotated by rotation of said shell, a trigger mechanism pivotally mounted on said driving disk, said trigger mechanism having an outwardly extending lug and a laterally bent toe, said clutch including an additional driven disk connected to said reset shaft, said disks and said shell having a common central axis concentrically mounted with respect to the axis of said driving shaft and said reset shaft, said second disk having a surface adapted to be engaged by said trigger mechanism to form a driving engagement between said first disk and said driven disk, whereby upon rotation of said driving shaft said second driven disk is rotated by said first disk through the agency of said trigger, and whereby when said reset shaft stops said toe of said trigger will be disengaged from the surface of said cam to break the driving connection and permit the spring in said computer to reversely rotate the driven disk 45 degrees, said shell having means adapted to engage the radially disposed lug on said trigger and said driven disk having a radially disposed lug adapted to engage the peripherally disposed lug on said shell.

16. A clutch for interconnecting a driving shaft and a reset shaft of a computer of the type having a reset shaft inoperable when the computer is being driven and wherein said shaft is turned 405 degrees in one direction to reset the computer and then stops and wherein said reset shaft then rotates reversely 45 degrees, said driving shaft and reset shaft being disposed in alignment and said clutch concentrically surrounding the axis of rotation of said shafts, and said clutch including a driving member and a driven member and a spring interconnecting said driving and driven members, and said clutch including an additional driven member and a disconnectable driving means between said first driven member and said additional driven member and operable when said reset mechanism of the computer stops automatically to render inoperative the driving means between said first driving member and said driven member upon the completion of the resetting operation and thereby to permit said reset shaft to be reversely rotated 45 degrees by the spring mechanism in the computer.

17. A liquid dispensing apparatus comprising a liquid dispensing line adapted to be connected to a source of liquid supply, a pump in said line, a motor for driving the pump, a manually operated switch member for actuating the motor, means including a delivery valve controlling the flow of liquid through the dispensing line, register mechanism operable in accordance with the flow of liquid through the dispensing line, an hydraulic cylinder, a piston in the cylinder, connections from said cylinder to the flow line to cause the operation of said piston upon the creation of a pressure in the flow line, mechanism movably operated by the piston, means actuated by movement of said mechanism for operating the resetting mechanism, said mechanism upon a predetermined movement actuating said delivery valve, and latching means disposed in the path of movement of said mechanism and co-operating with the switch operating mechanism

21

of the motor for preventing two consecutive movements of the switch operating mechanism to pump operating position unless the resetting mechanism has completed its full resetting travel.

18. A liquid dispensing apparatus comprising a dispensing line adapted to be connected to a source of liquid supply, register mechanism operable in accordance with the flow of liquid through the dispensing line, resetting means for the register mechanism, means responsive to the pressure of the fluid in said dispensing line for operating said resetting means, control means for effecting the operation of the register resetting means, said control means including mechanism to cause the complete automatic cyclic operation of the resetting means before said control means can be actuated again.

19. A fluid dispensing apparatus comprising a dispensing line adapted to be connected to a source of liquid supply, means for controlling the flow of liquid through the dispensing line, register mechanism operable in accordance with the flow of fluid through the dispensing line, resetting means for the register mechanism, means responsive to the pressure of the fluid in said dispensing line for operating said resetting means, control means for effecting the operation of the register resetting means, said control means including mechanism for operating the flow control means in predetermined timed relation to the operation of the resetting means, and means operable upon the actuation of said control means to cause the complete automatic cyclic operation of said resetting means before the control means can be operated again.

20. A liquid dispensing apparatus comprising a dispensing line adapted to be connected to a source of liquid supply, pump means for forcing liquid through said line, switch means for controlling said pump means, a register mechanism operable in accordance with the flow of liquid through said line, resetting means for said register mechanism, means responsive to the pressure of the fluid in said dispensing line for operating said resetting means, control means for effecting the operation of said switch means and said resetting means, and means for holding said resetting means at the position occupied at the end of the resetting stroke until said control means is actuated again.

21. A liquid dispensing apparatus comprising a dispensing line adapted to be connected to a source of liquid supply, pump means for forcing liquid through said line, switch means for controlling said pump means, a register mechanism operable in accordance with the flow of liquid through said line, resetting means for said register mechanism, means responsive to the pressure of the fluid in said dispensing line for operating said resetting means, control means for effecting the operation of said switch means and said resetting means, and means for holding said resetting means at the position occupied at the termination of the resetting operation until said control means is thrown to such a position that the pumping means is rendered inoperative.

22. A liquid dispensing apparatus comprising a dispensing line adapted to be connected to a source of liquid supply, pump means for forcing liquid through said line, switch means for controlling said pump means, a register mechanism operable in accordance with the flow of liquid through said line, resetting means for said register mechanism, means responsive to the pressure of the fluid in said dispensing line for operating

22

said resetting means, control means for effecting the operation of said switch means and said resetting means, means for holding said resetting means at the position occupied at the end of the resetting operation, and linkage means interconnecting said holding means and said control means effective to release said resetting means from said holding means when the control means is thrown to such a position that the pumping means is rendered inoperative.

23. A liquid dispensing apparatus comprising a dispensing line adapted to be connected to a source of liquid supply, pumping means for forcing liquid through said line, switch means for controlling said pumping means, a register mechanism operable in accordance with the flow of fluid through said line, a resetting means for said register mechanism, means responsive to the pressure of the fluid in said dispensing line for operating said resetting means, control means for effecting the operation of said switch means and said resetting means, said control means including mechanism to cause the complete automatic cyclic operation of the resetting means before said control means can be operated again, and means for holding said resetting means in the position occupied after the completion of the resetting operation until said control means is thrown to such a position that the pumping means is rendered inoperative.

24. A clutch for interconnecting a driving shaft and a reset shaft of a computer of the type having a reset shaft inoperative when the computer is being driven and wherein said shaft is turned 405° in one direction to reset the computer and then stops and wherein said reset shaft then rotates reversely 45°, said driving shaft and reset shaft being disposed in alignment and said clutch concentrically surrounding the axis of rotation of said shafts, said clutch including a driving member attached to said driving shaft and a latch means pivotally mounted on said driving member, a driven member having a cam surface with a recessed portion formed thereon, said latch means having an anti-friction member mounted thereon, said anti-friction member being urged against said cam surface and into said recessed portion by a spring interconnecting said latch means and said driving member whereby to interconnect said driving member and said driven member during the reset operation and operable when said reset mechanism of the computer stops automatically to render inoperative the driving connection between said driving member and said driven member upon completion of the resetting operation and whereby to permit said reset shaft to be reversely rotated 45° by the spring mechanism in the computer.

25. A liquid dispensing apparatus comprising a dispensing line adapted to be connected to a source of liquid supply, a valve means for controlling the flow of liquid through the dispensing line, register mechanism operable in accordance with the flow of liquid through the dispensing line, resetting means for the register mechanism, automatic control means for operating said resetting means and opening said valve means, and hydraulic means operated by the pressure of the liquid in the dispensing line for actuating said automatic control means, said control means completing the resetting of said register mechanism before opening said valve means whereby to insure that all liquid passing through the dispensing line is registered on the register mechanism.

23

26. A liquid dispensing apparatus comprising a dispensing line adapted to be connected to a source of liquid supply, pumping means for forcing liquid through the dispensing line, valve means for controlling the flow of liquid through the dispensing line, register mechanism operable in accordance with the flow of liquid through the dispensing line, resetting means for the register mechanism, switch means for effecting the operation of the pumping means, actuating means for said resetting means and said valve means, and hydraulic means operated by the liquid pressure in said dispensing line for operating said actuating means, said actuating means completing the resetting of the register mechanism before opening said valve means whereby to insure that all liquid passing through said dispensing line is registered on said register mechanism.

27. A liquid dispensing apparatus comprising a dispensing line adapted to be connected to a source of liquid supply, valve means for controlling the flow of liquid through the dispensing line, register mechanism operable in accordance with the flow of liquid through the dispensing line, resetting means for the register mechanism, control means for effecting the opening of said valve means and the operation of said resetting means, said control means being actuated by the pressure of the liquid in the dispensing line and effective to complete the operation of said resetting means before opening said valve means, and means for holding said resetting means at the position occupied at the end of the resetting stroke until said control means is actuated.

24

28. A liquid dispensing apparatus comprising a dispensing line adapted to be connected to a source of liquid supply, valve means for controlling the flow of liquid through said dispensing line, pump means for forcing liquid through said dispensing line, switch means for controlling said pump means, a register mechanism operable in accordance with the flow of liquid through said dispensing line, resetting means for said register mechanism, means responsive to the pressure of the fluid in said dispensing line for operating said resetting means and opening said valve means, said last mentioned means opening said valve means only after said resetting means has completed the resetting operation, control means for effecting the operation of said switch means, and means for holding said resetting means at the position occupied at the end of the resetting stroke until said control means is actuated.
